US00D693732S

(12) **United States Design Patent**
Dunn

(10) **Patent No.:** **US D693,732 S**
(45) **Date of Patent:** ** *Nov. 19, 2013

(54) **FLAG DISPLAY HOLDER FOR A CORD**

(76) Inventor: **Scott E. Dunn**, Atlanta, GA (US)

(*) Notice: This patent is subject to a terminal disclaimer.

(**) Term: **14 Years**

(21) Appl. No.: **29/431,054**

(22) Filed: **Aug. 31, 2012**

(51) **LOC (9) Cl.** **11-02**

(52) **U.S. Cl.**

USPC **D11/184**

(58) **Field of Classification Search**

USPC ..... D11/184; D8/105, 107, 333, 349, 354, D8/356, 358, 367, 373, 382, 383, D8/394-396; D23/261; D26/38; 24/197, 24/561; 174/153 G; 242/400.1, 405.1, 242/405.2, 600, 916; 248/65, 74.1-74.4, 248/214, 215, 229.26, 201, 302, 204, 316.7, 248/316.8; 439/501; D34/38; 108/57.52; D24/128

(57) **CLAIM**

The ornamental design for a flag display holder for a cord, as shown and described.

DESCRIPTION

FIG. 1 is a front perspective view of an embodiment of a flag display holder for a cord of the present invention;

FIG. 2 is a front elevational view of the flag display holder for a cord of FIG. 1;

FIG. 3 is a rear elevational view of the flag display holder for a cord of FIG. 1;

FIG. 4 is a left side elevational view of the flag display holder for a cord of FIG. 1;

FIG. 5 is a right side elevational view of the flag display holder for a cord of FIG. 1;

FIG. 6 is a top plan view of the flag display holder for a cord of FIG. 1;

FIG. 7 is a bottom plan view of the flag display holder for a cord of FIG. 1; and,

FIG. 8 is a rear perspective view of the flag display holder for a cord of FIG. 1.
